SHOVELS AND LIKE HAND TOOLS

Charles W. McDonald, Belpre, Ohio, assignor to McDonough Co., doing business as O. Ames Co., Parkersburg, W. Va., a corporation of Delaware

Filed Mar. 14, 1962, Ser. No. 179,692

1 Claim. (Cl. 294—54)

This invention relates to hand tools having a blade or head and a handle, and in particular to shovels, and the object is to provide a simple and efficient construction whereby the handle and blade may be firmly and permanently united not only by one unskilled in the use of tools, but even by one unprovided with any tools.

An important advantage is that the blades and handles may be shipped separately in more compact and convenient packages. The assembly may occur at the point of ultimate sale or a blade and a handle may be delivered separately to the ultimate user. He can make a perfect and permanent assembly, although he has no access to even such simple equipment as a vise, a hammer, a boring tool, a drive punch or a wrench, and perhaps would be unable to drive a nail efficiently, much less to set a rivet.

Because it displays the advantages of the invention in marked degree, I have shown in the accompanying drawings as an example of its application a snow shovel of the type sold to householders for domestic use with a blade of large area typically formed from a thin sheet of aluminum. The demands on such a shovel do not compare with those on a shovel for handling ore, for example, or one that is a production tool in regular use throughout long periods, but it should be a unitary tool not loose or wobbly or likely to become so, and durable of its kind.

The invention will be well understood by reference to the following description taken in connection with the accompanying drawings of an illustrative embodiment of the invention as applied to such a snow shovel:

FIG. 1 is a perspective view of the completed shovel as seen from the back side;

FIG. 2 is a section on line 2—2 of FIG. 1 on an enlarged scale;

FIG. 3 is a fragmentary elevation of the shovel as seen from the back side;

FIG. 4 is a section on line 4—4 of FIG. 2; and

FIG. 5 is a section on line 5—5 of FIG. 2.

The words "down," "up," "forward" and "rearward" and their derivatives are used from the point of view of a user holding the shovel in his hands ready to take up a shovelful.

Referring to the drawings, the snow shovel herein shown as an example of the invention comprises a blade B of thin sheet aluminum, having a steel edge E and reinforced by expressed ribs R. The handle H in this case is a cylinder of wood, provided with a cross grip G of the D type. The blade is not completely flat, but curved or bent so that the rearward part is displaced upwardly and forwardly to provide a proper "lift" in the shovel.

In the shovel illustrated the handle is fitted into a socket defined by the cooperation with the rearward portion of the blade of a fitting F, which fitting is formed of relatively heavy metal with a downwardly expressed central portion 10 and an out-turned flange 12 secured at the back of the blade by rivets 14 to define a socket at the back of the blade for receiving the end of the handle. Such a construction broadly is old in shovels of this type wherein the end of the handle is received in a socket provided between a fitting and the overlying portion of the blade, in which socket the handle has been secured by vertical rivets. Even if we assume the holes to be pre-formed, the ordinary purchaser of a snow shovel could not conveniently line them up and would be quite unable to make a workmanlike job of heading over iron rivets.

2

Referring now to FIGS. 2, 4 and 5, the rear portion of the fitting F comprises a semi-cylindrical portion corresponding to the diameter of the handle from which depend tangentially sides out-turned to form part of the flange 12 and the blade, as seen in FIG. 4, extends like a beam between these parts of the flange. The blade may have a slight depression 16 stamped therein to fit the upward side of the handle end when inserted. While the socket so provided is not completely cylindrical so that it fits the handle throughout its circumference, it provides a nice fit for the handle. As seen in FIG. 2 this rearward portion of the fitting extends forwardly for a distance corresponding to that portion of the length of the handle which it is desired to secure therein. The forward portion of the fitting may then be curved to correspond to the curve of the back of the blade and be tapered upwardly and sideways as seen in FIGS. 1, 2 and 3, providing a strong central rib supporting the central portion of the blade for a large fraction of its depth.

The handle receiving rearward portion of the fitting is provided with a longitudinal keyway 18 consisting (see FIGS. 2, 4 and 5) of two outwardly expressed ribs defining inwardly facing grooves between which the keyway is interrupted by the portion 20 which desirably has an abrupt shoulder at the forward side and a more oblique shoulder at the rearward side for a purpose which will appear. The handle is provided with a cooperating key which in the present instance is formed by the crossbar 22 of a staple, the crossbar being of a size to fit in the keyway, the staple having legs 24 driven directly into the wood of the handle.

To assemble the handle with the blade the lower end of the latter (viewing FIG. 2) is presented to the end of the socket with the key 22 opposite the open end of the keyway as seen in dotted lines in FIG. 2. When the key enters the keyway it properly positions the handle angularly so that the cross grip of the D handle G is in the proper position. The fit of the handle in the socket is a nice one, not a loose one, but the shovel and handle may be stood on end with the grip end toward the floor and a series of taps against the floor will drive it into the socket. Perhaps the central portion of the blade, bridging the sides of the fitting, springs a little during this operation, but the action is not easily perceptible if it occurs, and the blade is not permanently bent. When the crossbar of the staple reaches the interruption 20, inward movement is not completely blocked, and the tapping action causes the crossbar of the staple to pass the interruption and enter the forward end of the keyway beyond the abrupt shoulder as the handle goes home, which may be indicated if desired by a mark on the handle or an omission in the finish of the handle on the end which is to be received in the socket. The cooperation of the key and keyway prevent twisting of the blade about the axis of the handle and the engagement of the key with the abrupt shoulder of part 20 effectively resists withdrawal of the handle under such strains as the shovel is subjected to in use.

There are no loose parts. No skill is required to assemble the handle and blade and no tools, but a permanently connected handle having a life comparable to that of the shovel is provided. In the case of a handle broken off short as might happen, for instance if the handle was run over by the wheel of an automobile, it would be possible to split up and withdraw the stump without damaging the socket and a new handle with a similar key could be assembled.

I am aware that the invention may be embodied in other specific forms without departing from the spirit or essential attributes thereof, and I therefore desire the present embodiment to be considered in all respects as illustrative and not restrictive, as is in fact clear in several

matters from the description itself. Reference is to be had to the appended claim to indicate those principles of the invention exemplified by the particular embodiment described and which I desire to secure by Letters Patent.

I claim:

A shovel of the snow type comprising a blade of large area and a wooden bar handle, the shovel adapted for knocked-down shipment for subsequent assembly through the medium of interconnecting means comprising a fitting having a channeled portion with out-turned flanges secured to the back of the blade at its rearward side and providing a reinforcement for the same, the channel being open at the rear to receive within it the end of said handle entered between the same and the blade, the channeled portion of said fitting having along its inner side a keyway opening at the rearward end thereof, there being an obstruction in the forward part of the keyway including an abrupt shoulder at the forward end thereof providing a forwardly facing locking shoulder and a more oblique portion at the rearward end of said obstruction, and said

handle nicely filling the space between the channel and the blade and having a staple with arms driven into the wood of the handle so that the staple crossbar is disposed longitudinally of the handle and forms a key fitting the keyway of the blade and to be guided thereby, said staple crossbar key presenting a rearwardly facing shoulder to engage the forwardly facing locking shoulder of the blade fitting when the key is moved past the latter.
